IV | FIG. 3

INVENTOR:
RUSSELL J. WOODRUFF

or
George W. Seguill
ATTORNEY.

UNITED STATES PATENT OFFICE.

RUSSELL J. WOODRUFF, OF CLEVELAND, OHIO.

PISTON.

Application filed December 22, 1921. Serial No. 524,055.

To all whom it may concern:

Be it known that I, RUSSELL J. WOODRUFF, a citizen of the United States, resident of Cleveland, county of Cuyahoga, and 5 State of Ohio, have invented new and useful Improvements in Pistons, of which the following is a specification, the principle of the invention being herein explained, and the best mode in which I have contemplated applying that principle, so as to distinguish it from other inventions.

My invention relates to pistons and particularly to means of this character adapted for use in internal combustion engines. 15 The purpose of the invention is to design a piston which shall have an efficient bearing in the cylinder; which shall provide satisfactorily quick cooling of the piston head; and which shall provide automatic adjustment for the differential in the heating and cooling of the piston skirt and piston head. This piston is a composite structure and possesses advantages incident to the afore-described design which will be hereinafter 20 discussed in detail.

The annexed drawings and the following description set forth in detail certain means embodying my invention, the disclosed means, however, constituting but one of the 30 various forms in which the principle of the invention may be employed.

In said annexed drawings:

Figure 1 represents an elevation of my improved piston, the piston skirt being 35 shown in section and the usual wrist pin and connecting rod being omitted;

Figure 2 represents a horizontal section, taken in the planes indicated by the line II-II, Figure 3;

40 Figure 3 represents a vertical section, taken in the planes indicated by the line III-III, Figure 2; and

Figure 4 represents a vertical section, taken in the plane indicated by the line 45 IV-IV, Figure 3.

Referring to the annexed drawings in which the several elements are indicated by the same respective ordinals in the different views, the wall of an internal combustion engine cylinder is suggested by the 50 ordinal 1, within which is guided the skirt 2 of my improved piston. This skirt 2 may be of any suitable wear-resisting material having a relatively low coefficient of thermal expansion and a relatively low heat conductivity, such as cast-iron or a section

of steel tubing, and for the purposes of illustration in this specification, I shall describe this skirt 2 as made of cast-iron. The head 3 of my improved piston is formed of an 60 alloy or a metal having a relatively high coefficient of thermal expansion and relatively rapid heat conductivity and for the purposes of illustration, I shall describe the head 3 of this specification as made of 65 aluminum. The head 3 is formed with exterior grooves 4 to receive the usual piston rings 5; has a pair of integral diametrically opposed downwardly extending lugs 6 formed with integral inwardly extending 70 bosses 7 adapted to receive and accommodate the usual piston wrist pin 8. A reinforcing rib 9 is formed integrally with the head 3 and runs transversely across the inner face of the latter and is provided with 75 integral downwardly extending portions 9' integrally connecting with the upper part of the wrist pin bosses 7, as plainly shown in Figure 4.

I shall now describe means for connecting together the skirt 2 and head 3. For this purpose I form the head 3 with an annular series of downwardly extending ears 10 which are secured to the skirt 2 and as illustrating one approved method of so securing these ears 10 I show the same provided with tapped holes for receiving suitable screws 11 which are passed through the wall of the skirt 2 adjacently the upper edge of the latter and are preferably 80 counter-sunk in said wall, as plainly shown in Figure 3.

Preferably, the aluminum head 3 is somewhat smaller in diameter than the skirt 2, approximately .010 inch to .015 inch smaller 95 so that whereas the skirt 2 has a running fit in the cylinder 1, the aluminum head 3 can expand the necessary amount greater than the expansion of the cast-iron skirt 2. My means for connecting the skirt 2 and head 100 3 are very efficient and yet adequately provide for the necessary adjustment of the head and skirt due to their different coefficients of expansion, the ears 10 having enough spring to compensate for this difference of expansion between the bottom of the head 3 and the top of the skirt 2. Preferably, the flexible ears 10 are cast integrally with the aluminum head 3. Preferably, although not necessarily, I undercut the ears 110 10, as indicated by the ordinal 12, better to allow for the necessary spring of these ears.

when compensating for the different expansions of the skirt 2 and head 3.

What I claim is:

1. A piston for an internal combustion engine comprising a guide section and a head section of different materials; and flexible means for securing together said two sections, whereby adjustment is allowed for the differential in expansion. 35
2. A piston for an internal combustion engine comprising a guide section and a head section of different materials, one of said sections being formed with flexible ears; and means for securing said ears to 40
- 15 the other section, whereby adjustment is allowed for the differential in expansion. 45
3. A piston for an internal combustion engine comprising a guide section of material having a relatively low coefficient of 50
- 20 thermal expansion; a head section of material having a relatively high coefficient of thermal expansion, said head section being formed with a series of flexible ears; and means for securing said ears to said guide 55
- 25 section, whereby adjustment is allowed for the differential in expansion. 60
4. A piston for an internal combustion engine comprising a cast-iron guide section; an aluminum head section formed with a series of integrally cast flexible ears; and means for securing said ears to said guide section, whereby adjustment is allowed for the differential in expansion. 65
5. A piston for an internal combustion

engine comprising a cast-iron guide section; an aluminum head section, the latter being formed with a series of downwardly extending tapped flexible ears; and screws securing said ears to said guide section, whereby adjustment is allowed for the differential in expansion. 40

6. A piston for an internal combustion engine comprising a cast-iron guide section; an aluminum head section of smaller diameter; and flexible means for securing together said two sections, whereby adjustment is allowed for the differential in expansion. 45

7. A piston for an internal combustion engine comprising a cast-iron guide section; an aluminum head section of smaller diameter, said head section being formed with a series of downwardly extending tapped flexible ears; and screws securing said ears to said guide section, whereby adjustment is allowed for the differential in expansion. 50

8. A piston for an internal combustion engine comprising a cast-iron guide section; an aluminum head section, the latter being formed with a series of downwardly extended ears having undercut grooves in the sections joining the ears to the head; and means for securing said ears to said guide section. 60

Signed by me this 12th day of December, 1921.

RUSSELL J. WOODRUFF.
